(57) **CLAIM**

I claim the ornamental design for air module, as shown and described.

DESCRIPTION

FIG. 1 is a perspective view of air module showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is another perspective view thereof, shown in a position of use with a dispenser.

The broken lines showing portions of the air module and the dispenser form no part of the claimed design.
